UNITED STATES PATENT OFFICE.

PHILIP J. GRAU, OF TYRONE, PENNSYLVANIA.

FURNACE FOR STEAM-BOILERS.

SPECIFICATION forming part of Letters Patent No. 746,957, dated December 15, 1908.

Application filed October 15, 1902. Serial No. 127,319. (No model.)

To all whom it may concern:

Be it known that I, PHILIP J. GRAU, of Tyrone, county of Blair, State of Pennsylvania, have invented an Improvement in Furnaces for Steam-Boilers, of which the following is a specification.

My invention has reference to furnaces for steam-boilers; and it consists of certain improvements which are fully set forth in the following specification and shown in the accompanying drawings, which form a part thereof.

The object of my invention is to provide a construction of boiler-setting which shall supply the furnace with superheated air at the bridge to consume the carbon-dust and smoke or unburned gases passing from the furnace under the boiler and at the same time cause the air in the act of being heated to cool the side walls or lining of the furnace proper, as pointed out hereinafter.

My invention consists in providing the side walls of the furnace with flues through which air is forced to cool the said side walls and also cause the air to be superheated, the said furnace being further provided with a bridge formed of flues through which the air from the side walls is allowed to escape for the purpose of burning the gases, carbon particles, and smoke passing from the furnace.

My invention also comprehends details of construction which, together with the above features, will be better understood by reference to the drawings, in which—

Figure 1 is a sectional elevation through a furnace, showing my improvements applied to steam-boilers, the said section being taken on the line *z z* of Fig. 2. Fig. 2 is a sectional plan view of same on line *x x* of Fig. 1. Fig. 3 is a vertical sectional plan view of same on line *y y* of Fig. 1. Fig. 4 is a vertical section through the upper part of the bridge-wall and column, taken on the line *w w* of Fig. 5; and Fig. 5 is a transverse section of the said column on line *s s* of Fig. 4.

A represents a steam-boiler and may be of any suitable construction.

B represents the grate-bars, and C is the bridge-wall at the rear of the grate-bars. The upper portion or cap of the bridge-wall I form of fire-brick, preferably molded into a tubu-

lar box D, with an inclined front wall having a longitudinal air-passage *d* and a series of apertures at the top for receiving the air-columns.

E shows a series of air-columns, preferably triangular in cross-section, so as to present toward the grate-bars two inclined walls *e*. The lower part of these columns is provided with shanks T, adapted to fit into the upper part of the box-shaped fire-brick cap D of the bridge, as is clearly shown in Fig. 4. The rear portion of each of the columns may be provided with a foot-piece S to act as the strut in supporting the columns E against backward pressure, and thereby make it still more stable in its setting upon the box part D. The columns E are formed of fire-brick or other suitable refractory material and are provided with a vertical flue or passage-way R, opening at the bottom into the passage-way *d* of the bridge-cap D. The inclined faces *e* of the columns are provided with a series of apertures *r*, opening from the passage-way R. The height of the columns is preferably such as to fit approximately to the under side of the boiler, as is shown clearly in Fig. 3, but would of course be shaped differently with different boilers. The series of vertical columns E (of which there may be any number) form between them throats L, gradually lessening in width as they approach from the front to the rear. The columns E may be staggered, if desired, as indicated in dotted lines in Fig. 2.

The side walls K' of the furnace are lined with inverted-L-shaped fire-brick, which when assembled form a series of inclosed passage-ways *k* of sinuous form opening at the front of the boiler-setting into the air-supply pipes H' and at the cap D. The supply-pipes H' are provided with valves *h* of suitable construction and connect with a main flue H², extending under the floor to the blower J. A valve I' may be employed in this main flue H² to control the flow of air through it.

Air may be admitted to the bridge-cap D through a hollow floor F, which may be provided with a series of baffle-plates or walls *f*, forming a sinuous passage-way G, communicating at one end of the cap D and at the

free end in a pipe H, provided with a suitable valve I and, if desired, communicating with a blower or fan J of any suitable construction. The blower J may be omitted, if desired. In this manner the air passing through the floor F becomes superheated and emerges from the apertures r of the columns E in a highly-superheated condition, it being first heated in the floor F and then superheated to a greater extent in passing through the bridge-wall and columns. When the air escapes from the columns, it is directed toward the passing products of combustion and is carried backward with said products of combustion and forced into intimate contact therewith while the said products are passing over the highly-heated surface of the columns, thus insuring the most thorough commingling and superheating of the entire gases. As these combined gases pass through the throats L they are condensed into the most thorough contact or admixture and lead from the rear in strong heating-flames. It will now be seen that the air may be directed wholly through the hollow-floor superheater F on its way to the bridge-cap flue d or wholly through the main H² and the side flues k of the furnace-walls K' or wholly through each of the superheating devices, as desired. The air in either case is thoroughly heated before emerging from the upright columns E, and in case of the side flues k it may be regulated to insure a proper quantity of air passing through each of the walls K'. While these furnace side walls act as perfect superheaters for the air, the air, on the other hand, keeps them from overheating and burning out. This construction overcomes the destruction difficulty which so frequently occurs in furnaces of ordinary construction by insuring exceptionally long life to the lining. Aside from the saving in expense in labor and material there is also the great saving in loss of use of the boiler, which loss heretofore occurred whenever the side walls were required to be rebuilt. The side walls may be of any length found convenient and formed in any way desired so long as they cool the lining and act as flues for conveyance of air.

Where it is not desired to superheat the air before passing through the columns, it may be directly passed into the box-cap D by an air-flue H³, provided with a suitable valve L³, which may be controlled by a chain i, as clearly shown in Figs. 2 and 3. In some cases it is not desired to admit air from the columns E at all, as the superheating effect of the said columns of refractory material insures all the requirements where a slower and more uniform temperature is necessary.

The minor details may be modified without departing from the spirit of the invention.

What I claim as new, and desire to secure by Letters Patent, is—

1. In a furnace for steam-boilers, the combination of the grate with side walls provided with sinuous air-passages formed by L-shaped fire-brick, a hollow bridge-wall having openings in its upper surface, and receiving heated air from the passages in the side walls, means for forcing air through the passages of the side walls, hollow columns of refractory material fitted into said openings and having inclined faces at the front or forward end provided with air-orifices opening through them into the interior and which columns are so arranged as to form a series of parallel vertical passages through which the products of combustion from the grate are required to pass.

2. In a furnace for steam-boilers, the combination of the grate, side walls on each side of the grate provided with air-passages, arranged in sinuous form adapted to receive the air at the top and deliver it from the bottom in heated condition, a hollow bridge-wall having openings into the lower parts of the air-passages and also into the furnace-space above the grate, a blower, pipes leading from the blower to the upper part of the air-passages, and separate valves for controlling the supply of air to each of the air-passages.

3. In a furnace for steam-boilers, the combination of the grate, two independent and parallel side walls on each side of the grate provided with air-passages formed in sinuous form therein by the fire-brick lining, means for independently circulating air through the air-passages of the two side walls from the top downward, and a transverse passage-way across the rear of the fire-box in which the lower part of each of the passage-ways open and provided with apertures through which the combined heated currents of air pass into the furnace.

4. In a furnace for steam-boilers, the combination of the grate, side walls on each side of the grate provided with continuous parallel air-passages formed therein by the fire-brick lining, said lining consisting of independent L-shaped blocks of fire-brick resting upon each other in layers as shown and forming continuous closed horizontal and vertical walls.

In testimony of which invention I have hereunto set my hand.

PHILIP J. GRAU.
